JULIUS L. SCHNELL, OF ARLINGTON, NEW JERSEY

DESK SET

Application filed May 8, 1929. Serial No. 361,286.

The invention relates to improvements in desk sets and has for its object to provide a means of exceedingly simple nature whereby the writing instrument or holder is easily removed from the funnel of the desk set and positively prevented from binding or becoming stuck or frozen in the funnel.

Ordinarily desk sets of the type to which the invention relates are provided with a hard 10 rubber funnel and a holder made of a similar material. When not in use the holder is inserted into the funnel and is held there by friction. Very often the holder is inserted in the funnel somewhat harder than necessary. 15 When it is desired to remove it again considerable force must be used in withdrawing it. This entails many disadvantages.

The base of the desk set which is made of a substantial heavy material is often lifted 20 bodily when withdrawing the holder. This is very annoying as it may slam back and scratch the desk and the jerk that is given as the holder leaves the funnel will result in ink being spattered from the pen. In cases where 25 ink has congealed on the holder and the holder has been inserted into the funnel with undue effort the holder has actually been broken off in removing it from the funnel and it has been necessary to drill out the part 30 remaining in the funnel.

It is also very bothersome when a person is using the desk set to be forced to hold the base and funnel with one hand and remove the holder with the other. The holders also 35 are very often scratched and marred in their appearance due to the harsh friction set up between the hard materials of the funnel and holder.

Funnel have been provided with a large 40 mouth and spring clips below the mouth to maintain the holder in position. While this construction eliminates some of the difficulties it is also disadvantageous due to the fact that an excessive amount of air is supplied to 45 the pen point. This will result in the ink drying or hardening around the point and the feed and the pen will not be ready for use when withdrawn from the funnel.

The present invention contemplates the 50 elimination of these serious faults by provid-

ing a simple means adjacent the mouth of the holder for positively maintaining the holder in position in the funnel without setting up undue friction and permitting at all times of the easy withdrawal of the holder regardless 55 of the fact that it may have been inserted with unnecessary vigor.

Other objects and advantages will become apparent as this specification proceeds. Referring to the drawings forming a part thereof and in which a preferred embodiment of the invention is illustrated:

Fig. 1 is an elevational view of a desk set with the holder in position in the funnel. In this view part of the funnel is broken out and 60 in section to better illustrate the invention;

Fig. 2 is a fragmentary longitudinal sectional view of the funnel on a larger scale with the holder withdrawn and the parts positioned accordingly; 70

Fig. 3 is a cross sectional view taken on line 3-3 of Fig. 2;

Fig. 4 is a detail perspective view of the sliding friction sleeve which engages the holder when in position in the funnel; and 75

Fig. 5 is a detail perspective view of the threaded flanged member which acts as a stop in one direction for the friction sleeve and also provides an ornamentation for the funnel of the desk set. 80

Referring again to the drawings the reference numeral 6 designates the base of the desk set.

Swiveled or otherwise secured at 7 to said base is a funnel 8. When not in use the holder 85 9 is inserted into the funnel. The holder 9 as illustrated is a combination pen and pencil. However, it is to be understood that the holder 9 may be a writing instrument of any well-known form.

The funnel 8 is counterbored at 10 thus providing a smooth interior surface and a shoulder 11 at the base of the counterbore.

Slidably mounted in the counterbore 10 is a friction sleeve 12. This friction sleeve 95 is preferably made of a compressible resilient material. Cork has been found to be very satisfactory in practice but other materials could be readily substituted.

The mouth of the funnel is threaded for 100

the reception of a retaining ring 13. The retaining ring is externally threaded at 14 to engage the interior threads at the mouth of the funnel and is provided with a flat sloping flange 15. This flange insures the proper positioning of the retaining ring and when plated acts as a handsome ornamentation for the funnel.

The friction sleeve 12 fits snugly within 10 the counterbore 10 and the length of the sleeve is preferably somewhat less than the depth of the counterbore. When the holder 9 is inserted in the funnel it will be engaged by the upper end of the sleeve 12 and the 15 sleeve will be carried down until stopped by the shoulder 11. This position is illustrated in Fig. 1.

In removing the holder the sleeve 12 will be moved in the opposite direction and will 20 contact with the retaining ring 13 secured in the mouth of the holder. This contact will be sufficient to break the friction bond between the holder and the sleeve and thus permit of the easy withdrawal of the holder 25 from the funnel. Fig. 2 shows the position of the sleeve as the holder is being withdrawn. The movement of the sleeve 12 is so slight that it will not be felt by a person when inserting the holder into the funnel or with- 30 drawing it yet this slight upward movement and contact of the sleeve with the retaining ring is ample to make certain of the easy withdrawal of the holder even when it has been forced with undue vigor into the funnel.

35 The inside diameter of the ring 13 is somewhat greater than the inside diameter of the friction sleeve 12 so as to eliminate the possibility of holder 9 engaging the ring when being inserted into the funnel. The holder does not contact at any point with the funnel thus avoiding the harsh friction that would naturally be set up between the two hard 40 surfaces. The friction sleeve being made of a resilient compressible material and the holder only being gripped by the end of the sleeve the light friction thus established will always maintain the holder in its proper 45 position and as heretofore stated allow for its easy withdrawal at any time.

50 The friction sleeve may be rounded off slightly as indicated at 16 to allow easier insertion of the holder into the funnel. The sleeve may also be provided with a plurality of saw cuts or slots 17. The diameters of the 55 holders very often vary and the slots 17 will compensate for these variations.

A small opening 18 is provided in the funnel. This opening permits of sufficient air 60 entering the funnel to prevent the ink from running from the pen point but does not allow enough air to enter to dry or harden the ink about the point and feed portions of the pen.

From the foregoing description and an inspection of the drawings it will be apparent

that a simple and efficient means is provided for preventing the holder from binding or becoming frozen or stuck in the funnel. Changes may be made in details of construction by one skilled in the art without departing from the spirit of the invention as set forth in the appended claims.

I claim:

1. A desk set having in combination, a base, a funnel secured to said base, a friction sleeve 75 slidably mounted in said funnel adjacent the mouth thereof, said friction sleeve snugly fitting the interior of said funnel and being made of a compressible resilient material adapted to engage a holder when inserted 80 into said funnel and permitting of the easy withdrawal of the holder from said funnel, and a retaining ring secured in the mouth of said funnel to prevent said friction sleeve from being displaced in relation to said 85 funnel.

2. A desk set having in combination, a base, a funnel secured to said base, a friction sleeve made of a compressible resilient material, said funnel being counterbored and 90 said friction sleeve being slidably mounted in said counterbore, the shoulder formed by said counterbore acting as a stop to limit movement in one direction when a holder is being inserted into the funnel, and a retaining 95 ring secured in the mouth of said funnel, said retaining ring being adapted to limit movement in the opposite direction and act to break the friction bond between the holder and said friction sleeve when the holder is 100 being withdrawn from said funnel.

3. A desk set having in combination, a base, a funnel secured to said base, a friction sleeve made of a compressible resilient material, said funnel being counterbored and 105 said friction sleeve snugly fitting said counterbore and slidably mounted therein, a plurality of cuts in said friction sleeve to compensate for slight variations in the diameters of holders, the shoulder formed by said counterbore acting as a stop to limit movement in 110 one direction when a holder is being inserted into the funnel, and a retaining ring secured in the mouth of said funnel, said retaining ring being adapted to limit movement in the 115 opposite direction and act to break the friction bond between the holder and said friction sleeve when the holder is being withdrawn from said funnel.

4. A desk set having in combination, a base, a funnel secured to said base, a friction sleeve made of a compressible resilient material, said funnel being counterbored and said friction sleeve being slidably mounted in said counterbore, the shoulder formed by said 125 counterbore acting as a stop to limit movement in one direction when a holder is being inserted into the funnel, and a flanged retaining ring secured in the mouth of said funnel said retaining ring being adapted to limit 130

movement in the opposite direction and act to break the friction bond between the holder and said friction sleeve when the holder is being withdrawn from the funnel, the inside diameter of said retaining ring being more than the inside diameter of said friction ring so as to insure against the holder contacting with said retaining ring.

5. A funnel for a desk set having in combination, a friction sleeve made of a compressible resilient material slidably mounted in said funnel, a shoulder to limit the movement of said sleeve in one direction when a holder is being inserted into said funnel, and
10 a retaining ring secured in the mouth of said funnel to limit movement in the opposite direction and act to break the friction bond between the friction sleeve and the holder when the holder is being withdrawn from the
15 funnel.
